METHOD OF MODIFYING THE ACOUSTICS
OF A ROOMBernard Roux, Robert Gamzon, and Mario Sol-
lima, Paris, FranceApplication December 20, 1935, Serial No. 55,474
In France December 22, 1934

5 Claims. (Cl. 179—1)

This invention relates to a new or improved method of and means for improving or correcting the acoustics of a room, hall, studio or other enclosed space or auditorium.

5 Architects have experienced great difficulty in producing rooms having good acoustic qualities, which latter must include not only good intelligible hearing of speech but also an agreeable colour or tone in the hearing of musical performances. This difficulty, which occurs with rooms or halls intended for direct audition, is greater in the case of sound studios wherein microphones pick up sound to be transmitted or recorded. With such studios, the fear of sound

10 confusion resulting from echo has conducted to the employment of absorbent materials. This imparts a dead and dull tone which is very disagreeable from the point of view of musical aesthetics.

15 Recent studies have shown that, once the echoes are avoided, the artistic sound quality of a hall or studio depends solely upon reverberation characteristics for the different musical frequencies. The reverberation period of time (this

20 being the time during which the intensity of a simple sound, having its source of emission sharply arrested, falls to one millionth of its value) is not the same in one and the same room for all frequencies. It has been shown that

25 a hall, having acoustics suitable for speech and music, should have a greater reverberation period for deep and sharp or shrill sounds than for medium sounds. For the best effect, the reverberation period should vary as a function of the frequency following an optimum curve which, generally speaking, should be approached as closely as possible.

30 When troublesome echoes have been avoided in a hall or studio by suitable architectural or acoustic arrangements, it is often found that the reverberation curve has no relation whatever to the optimum curve above mentioned.

35 The object of the present invention is to provide a method and means for the regulatable correction or modification of the acoustics of a hall, room, or studio, thereby permitting of giving to an audience, without touching the form or nature of the walls, the impression of an acoustic property approaching the optimum curve aforesaid and variable at will.

40 According to this invention, reverberation periods, which are found to be insufficient for certain frequencies or zones of frequencies are lengthened by electrical means.

45 According to one practical method, a part of

the emitted sound is transmitted to a reverberation chamber having a large reverberation period but of small dimensions for avoiding echoes. A microphone placed in this chamber receives the sound reverberated. If it is a matter of correcting or modifying the acoustics of a hall in which an audience has direct hearing, the reverberated sound is returned by a system of amplifiers and loud speakers and is superimposed upon the sound emitted directly in the hall. In the case 10 of a sound studio, however, the reverberated sound may be mixed electrically with the sound normally picked up in such studio.

50 The invention further provides for the introduction of one or more electrical filter devices, 15 these devices having the function of affecting the sound intensity corresponding to a given frequency or frequencies. In practice, the more general arrangement would include a filter or filters affecting the intensities of the sounds of different zones or bands of musical frequencies according to a given coefficient or coefficients of weakening regulatable at the will of the operator. The filters aforesaid may be introduced in the circuit from the hall to the reverberation 20 chamber, or in the circuit from the reverberation chamber to the hall, or in the circuit from the reverberation chamber to the electrical mixer.

55 The total sound (direct sound plus reverberated sound)—or the equivalent modulations of electric current—then has, for each given frequency, a period of apparent reverberation which is greater as the aforesaid coefficient of weakening is less for that frequency. The maximum reverberation period, for a frequency or group 30 of frequencies, is that of the reverberation chamber for that frequency or group of frequencies.

60 In practice, and for any given auditorium, it is possible to obtain a desired curve, as follows:—

(1) Take the real curve representing the reverberation period of the auditorium as a function of the frequency.

(2) Compare that curve with the curve that 45 it is desired to obtain, for example, the optimum curve. (The problem can be resolved by this method only if the real curve does not present, for any frequency, a reverberation period greater than the corresponding period for the same frequency on the desired curve. This condition can always be realized by sufficiently deadening in its entirety the auditorium or studio concerned.)

(3) From the comparison is deduced the reverberation period that, for each given frequency 50

55

or zone of frequencies, should be added to the natural reverberation period of the auditorium or studio for that frequency or zone of frequencies.

5 As already indicated, the required addition is obtained by means of a reverberation chamber and one or more filters, the latter being adapted for giving to the appropriate frequency or group of frequencies the desired lengthening of the 10 reverberation period.

The result of the foregoing intuitive reasoning can be made mathematically precise, as follows:—

15 Consider a reverberation curve giving sound intensity as a function of time for a given frequency, the origin of time being the arrest of sound emission from its source. The scale of intensity is logarithmic and the scale of time is linear. The curve of reverberation for a given 20 frequency in the reverberation chamber is represented by a straight line A—B see Figure 4 of the accompanying drawing. The period of reverberation is O—B, the point O being 60 decibels beneath A. Let it be assumed, for simplicity, that 25 the auditorium, for the frequency in question, has no reverberation, then, if the filters and amplifiers are regulated for giving no weakening to the transmission of the sound reverberated, the total period of reverberation will be O—B.

30 If, by regulation of the filters and amplifiers a weakening of, say, 10 decibels is effected in the sound reverberated at the frequency in question, the curve will be displaced 10 decibels parallel with itself and the total curve will be A¹—B¹, 35 the apparent period of reverberation being O—B¹ which is less than O—B.

The regulation of the weakening of the intensity for each frequency (a weakening that can be obtained and regulated by known means) determines 40 therefore the apparent reverberation period for each frequency. In Figure 4, the reverberation period varies as the logarithm of the initial intensity of the sound reverberated.

If a weakening of 10 decibels is introduced in 45 the circuit of the sound to be reverberated, the total period of reverberation is reduced only one sixth of its previous value. On the other hand, and with the same conditions, the sound passing through the reverberation system, being 10 decibels weaker than the direct sound, can be considered as negligible relatively to the latter. This shows that the regulation of the filters of a system in accordance with the invention cannot, in practice, appreciably modify the curve of transmission of total resultant intensities from the initial source of sound to the sound recording or receiving apparatus, or to the ear of the audience. Its effect is manifested only upon the duration of reverberation.

60 The annexed drawing diagrammatically represents different examples of means for carrying out the invention.

Figures 1 and 2 are diagrams showing simple circuits leading to the reverberation chamber.

65 Figure 3 is a diagram showing a triple branch circuit leading to the reverberation chamber, and

Figure 4 is a diagram showing curves already referred to.

In Figures 1 to 3, S indicates an auditorium, 70 hall, or sound studio. C is the reverberation chamber. In the auditorium, a microphone m produces electrical modulations corresponding to the sounds emitted. D is a device for deviating a part of the modulations on to a branch circuit 75 ending in a loud speaker H in the reverberation

chamber C. Electrical amplifiers are indicated at P₁, P₂, P₃, P₄ and P₅, and the coefficient of amplification by these instruments may be regulatable or not.

In the chamber C a second microphone n picks 5 up the sound reverberated in that chamber and introduces it to a mixer M where it is mixed with the sound transmitted directly from the microphone m.

In Figure 1 an electric filter F is placed between 10 the microphone n and the mixer M for regulating the relation of the intensities for the different frequencies.

In Figure 2 a filter F₁ is placed between the device D and the loud speaker H. 15

In Figure 3, the circuit from the device D comprises three branches each including a regulatable amplifier, as indicated at P₁, P₂, and P₃. Each branch also includes a filter indicated at F_b, F_m and F_h, and ends at a loud speaker in 20 the chamber C, these loud speakers being indicated at H₁, H₂, and H₃.

The three filters F_b, F_m, F_h, are regulated so that each permits passage of an appropriate part of a sound. Thus, for example, the filter F_b may 25 be a low-pass filter permitting low tones to pass; the filter F_m may be a band-pass filter for passing medium tones, and the filter F_h may be a high-pass filter for the elevated tones.

The sound thus filtered is transmitted to the 30 loud speakers H₁, H₂, H₃. The acoustic mixture of sounds emitted by the loud speakers is reverberated in the chamber C and is then picked up by the microphone n and transmitted through the amplifier P₄ to the mixer M. In this example, 35 regulation of the reverberation curve can be accomplished by means of potentiometers, for instance, operating upon the amplification of the amplifiers P₁, P₂, P₃.

The several examples relate to the case where 40 the reverberated part of the transmission is mixed electrically with the part directly transmitted. Thus, they are concerned more particularly, with the taking of records on discs, films and so on, or, with the emissions of wireless 45 telegraphy.

It is to be understood that analogous arrangements could be utilized for the transmission to an auditorium of the part reverberated only. In this case, the circuit of the microphone n would 50 include one or several loud speakers placed in the auditorium at one or more suitable points.

Further, it is to be understood that the invention is not limited to the particular examples hereinbefore described and illustrated by the 55 drawing. In particular, it is not necessary that both the transmission of sound to the reverberation chamber and the transmission of reverberated sound from that chamber, should be effected by electrical means. One of the transmissions could be effected by electrical means and the other by acoustic means. Of course, the means for varying the intensity of the sound reverberated as a function of the frequencies will be in that part of the transmission which is 60 electrical.

Having now particularly described and ascertained the nature of our said invention and in what manner the same is to be performed, we declare that what we claim is:—

1. In an electro-acoustical apparatus for transmitting sounds, a sound transmitter, an acoustical echo device for artificially lengthening the reverberation period of the transmitted sounds, means for conveying to the echo device a part 75

of the energy coming from the transmitter, means for picking up the corresponding energy from the echo device and leading it to a receiver, one of the last named means being electrical, and electrical means combined with said electrical conveying means for affecting the intensities of the different musical frequencies conveyed, according to given coefficients of weakening regulatable at the will of the operator.

10 2. In electro-acoustical apparatus for the transmission of sounds, a transmitter for converting the sounds emitted into electrical currents, an acoustical echo room, means for carrying a part of said electrical currents to said echo room, means for converting the electrical currents into acoustical vibrations in said echo room, means for picking the reverberated vibrations from the echo room, means for again converting these vibrations into electrical currents, means for modifying at will the intensity of each of the various frequencies or groups of frequencies of the electrical currents leading to or coming from the echo room, means for receiving the currents coming directly from the transmitter as well as the currents coming from the echo room.

25 3. In electro-acoustical apparatus for the transmission of sounds, a transmitter for converting emitted sounds into electrical currents, means for directly leading a part of the electrical energy so generated to a receiving apparatus, means for carrying another part of said electrical current into a plurality of branches of current, a potentiometer and a selective filter on each branch, an echo room having loud speakers located therein, said branches leading to a loud speaker in said echo room, one or more microphones in the echo room and one or more electrical circuits

leading from said microphones to the first named receiving apparatus.

4. In an electro-acoustical apparatus for the transmission of sounds, a transmitter for converting emitted sounds into electrical currents, 5 an acoustical echo room, means for leading a part of said currents to said acoustical echo room, means for converting the electrical currents into acoustical vibrations in said echo room, means for picking the reverberated vibrations 10 from the echo room, means for again converting said vibrations into electrical currents, means for dividing said currents into a plurality of branches, a potentiometer and a selective filter on each branch, and means for receiving the currents 15 coming directly from the transmitter as well as the currents carried by the several branches.

5. In an electro-acoustical apparatus for the transmission of sounds, a non-damped auditorium, a transmitter located in said auditorium 20 for converting a part of sounds emitted in said auditorium into electrical currents, an acoustical echo room, means for leading said currents to said acoustical echo room, means for picking the sounds produced by these currents in said room 25 after reverberation, means for again converting these sounds into electrical currents, means for converting said currents into sounds, means for modifying at will the intensity of each of the various frequencies or groups of frequencies of 30 the electrical currents leading to or coming from the echo room and means for reinjecting into the auditorium the sounds produced by the currents coming from the echo room.
